W. B. KOCHENDERFER

KNITTING MACHINE

Filed July 3, 1922

UNITED STATES PATENT OFFICE.

WILLIAM B. KOCHENDERFER, OF CAMDEN, NEW JERSEY.

KNITTING MACHINE.

Application filed July 3, 1922. Serial No. 572,474.

To all whom it may concern:

Be it known that I, WILLIAM B. KOCHENDERFER, a citizen of the United States, and a resident of Camden, Camden County, 5 New Jersey, have invented certain new and useful Improvements in Knitting Machines, of which the following is a specification.

My invention relates to certain improvements in those types of knitting machines 10 wherein the knitting needles, as well as the thread-guides, are cast in "leads" and such "leads" are secured to bars; in the one instance to the needle bar and in the other instance to the thread-guide bar. Since my 15 invention relates to the manner of supporting the needles or thread-guides in the respective bars, it seems unnecessary to make any reference to the relation of these parts, or to the manner in which the same operate.

20 In practice, should any one of any group of needles or guides supported by the respective "leads" become damaged, it is necessary to remove the "lead" with the entire group of needles (or thread-guides carried thereby), melt the "lead", and then reassemble a perfect set of needles (or thread-guides) in a fresh "lead". This requires casting off of the stitches of such group of needles (or removal of the threads in the 25 case of thread-guides), and then relooping such stitches (or threading the guides). It will be understood, of course, that such removed "lead" containing a damaged needle (or thread-guide) is immediately replaced 30 by a new "lead" carrying a group of needles (or thread-guides); fully equipped replace parts being kept for the purpose.

One object of my invention is to provide 35 means whereby the needles (or thread-guides) may be individually mounted in and securely held to the respective bars, so that in case of accidental breakage, distortion, or other damage to a needle (or thread-guide) requiring replacement, the individual needle (or thread-guide) can be removed, and a perfect one replaced in an easy 45 and expeditious manner without dismantling the machine or affecting the work except in so far as the individual needle (or thread-guide) is concerned.

A further object of my invention is to 50 provide spacing means for the respective needles (or thread-guides) whereby the latter may be maintained in the desired 55 position with respect to the work in hand.

A further object of my invention is to

provide spacing members capable of tightly gripping the needles (or thread-guides) and securely holding them in proper position with respect to the bar supporting the same. 60

A further object of my invention is to provide spacing members which, while serving to grip the needles (or thread-guides) and hold the same in the assembled position, may be separated therefrom to permit withdrawal of a needle (or thread-guide), without disturbing the position of the spacing member in the bar or support or affecting its function upon restoration of fresh needle (or thread-guide), and a still further object of my invention is to provide efficient means for clamping the needles (or thread-guides) and the associated spacing members in a supporting bar or other mount. 70

These and other features of my invention 75 are more fully described hereinafter; reference being had to the accompanying drawings, in which:

Figure 1, is a front elevation of sufficient 80 of a needle (or thread-guide) bar or support, to illustrate my invention.

Fig. 2, is an end view of the structure shown in Fig. 1.

Fig. 3, is a plan view of the same.

Fig. 4, is a perspective view of a knitting 85 needle.

Fig. 5, is a perspective view of a thread-guide.

Fig. 6, is a perspective view of a spacing 90 member, within the scope of my invention, such as may be employed in assembling the knitting needles (or thread-guides) in the bar or support for the same, and

Fig. 7, is a fragmentary view on an enlarged scale showing the manner in which 95 the butts of the knitting needles (or thread-guides) are disposed with respect to the spacing members or elements.

In the drawings, which are more or less diagrammatic, 1 represents a bar or support, 100 L-shape in cross section in the present instance, which may serve as a support or mount for knitting needles (or thread-guides); such change in shape or design as may be necessary in practice to distinguish 105 between the two bars being such as the particular knitting machine requires, and the bar shown is merely illustrative of a needle (or thread-guide) mount or support which may be employed in carrying out my invention. 110

This bar is provided with the webs or

flanges 1^a and 1^b, substantially at right angles to each other, and the flange or web 1^a is slotted at 2; such slot extending from end to end of the bar and being designed to receive the needles (or thread-guides) of the type similar to those heretofore cast in and supported by "leads" subsequently secured to a bar or other form of mount.

The slot 2, is enlarged at its inner end, as indicated at 2^a; such enlargement providing shoulders 3, for a purpose hereinafter set forth. The type of knitting needle and thread-guide, clearly shown at 5 and 6, in Figs. 4 and 5, may have crimped or corrugated ends or butts 5^a and 6^a. In the former practice the crimped or corrugated portions were designed to be engaged by the "lead" in which they were cast whereby they could be securely held in position.

In carrying out my invention I propose to place between the respective needles (or thread-guides), one or more spacing members; which may be equal to the thickness or width of the needles, or greater or less as the case may be, but in all cases equal to the greatest dimension of the needle (or thread-guide) body so as to closely fit the slot 2 in which they are disposed; such spacing members being composed of a suitable compressible metal so as to be capable of tightly gripping the needles (or thread-guides) and hold them in proper position in the slot. While it is true that many metals may be employed within the scope of my invention for performing the desired function, I have found that I can employ an ordinary printing slug, of suitable gage, depending upon the gage or position of the needles (or thread-guides); such printing slug, clearly illustrated at 10, Figs. 6 and 7, being modified to the extent of providing a head 10^a of a size and shape to fit the enlarged portion 2^a of the slot 2, formed in the flange 1^a of the bar or support 1. In addition, in order that the pressure applied to grip the needles (or thread-guides) and spacing members to the bar 1 will not tend to prevent removal of a needle (or thread-guide), as the case may be, the heads 10^a are reduced on opposite sides as indicated at 10^b, so that said heads are thinner than the body of the spacing member and can accommodate the crimped or corrugated portions of the needle (or thread-guide) butts, without being so compressed with respect to the same as to make it difficult or impossible to remove a needle (or thread-guide) after backing off the clamping means employed to hold the needles (or thread-guides) and spacing members in the slot of the bar, as clearly shown in Fig. 7.

As may be readily understood, the needles (or thread-guides) and the spacing members may be alternately assembled, or placed in any desired relation in the slot 2 of the bar

1; extending therein from end to end of the same and substantially filling such slot. As may be further understood, the spacing members may occupy the place of needles (or thread-guides), where it is not necessary or desirable to fill the bar or support with the full complement of needles (or thread-guides) that it may carry.

In order to secure the needles (or thread-guides) with the spacing members, in place, each end of the bar (one end only being shown) is provided with an abutment 11, which may have a reduced and threaded portion 12, passing through the flange 1^b of the bar 1, and secured thereto by a nut 13. In addition, the abutment may be secured to the flange 1^a by a screw 14; the head of which may be disposed in a recess 15, in the abutment. A pressure-applying member 16, may be arranged at each end of the bar 1; such pressure-applying member lying in close contact with the flange 1^a of the bar 1 and having a tongue 17, adapted to enter the slot 2, of the flange 1^a, as clearly shown in Fig. 3, and to contact with a needle (or thread-guide), or spacing member, against which it may be forcibly pressed.

For this purpose, a threaded bolt 18, which may pass freely through an aperture in the abutment 11, engages a threaded opening 16^a in the pressure-applying member 16. By turning this bolt in the abutment, by the application of a suitable tool to its head 18^a, the pressure-applying member will be drawn along the flange 1^a, and its tongue will engage the end of the group of needles (or thread-guides) and spacing members and, in combination with similar means at the opposite end of the bar, clamp the same in the slot.

The metal of the spacing members is of such a character as to tightly grip the needles (or thread-guides) and hold them against removal. At the same time, by loosening the clamping means any damaged needle (or thread-guide) can be removed, without displacing the spacing members which will be retained in place by their heads 10^a engaging the shoulders formed by the enlarged portion 2^a of the slot 2.

While I have shown spacing members provided with rectangular heads fitting the enlarged portion 2^a of the slot, also illustrated as rectangular, it will be understood that such heads may be differently shaped, and that the groove may be correspondingly shaped to receive the same; the essential object being to provide a construction that will properly space and confine the needles (or thread-guides) and at the same time be held in the slot when it is desired to remove one or more needles (or thread-guides).

I claim:

1. The combination of a slotted bar, a group of thread-engaging members disposed

- in said slot, independent spacing members disposed between said thread-engaging members, and clamping means carried by said bar.
5. 2. The combination of a slotted bar, a group of thread-engaging members disposed in said slot, compressible metal spacing members disposed between said thread engaging members, and clamping means for 10 said several members carried by the ends of said bar.
3. The combination of a carrier bar having a slot, a group of thread-engaging members disposed in said slot, independent spacing members disposed between said thread-engaging members, clamping members between which the spacing members and thread-engaging members are held, and means for confining said clamping members 15 to the carrier bar to hold the thread-engaging and spacing members to said bar.
4. The combination of a carrier bar having a slot, a group of thread-engaging members disposed in said slot, compressible metal 20 spacing members disposed between said thread-engaging members, clamping members between which the spacing members and thread-engaging members are held and means for confining said clamping members 25 to the ends of the carrier bar to hold the thread-engaging and spacing members to said bar.
5. The combination of a slotted bar, a group of thread-engaging members mounted 30 in said slot, independent spacing members disposed between said thread-engaging
- members, and means for holding said thread-engaging and spacing members in close relationship to prevent dislodgment of said thread-engaging members. 40
6. The combination of a slotted bar, a group of thread-engaging members, a group of metal spacing members disposed between said thread-engaging members, and means for holding said thread-engaging and spacing members in close relationship to prevent dislodgment of said thread-engaging members. 45
7. The combination of a slotted bar; said slot having an enlarged bottom portion, a plurality of thread-engaging members mounted in said slot, spacing members disposed between said thread-engaging members, and means for clamping said thread-engaging and spacing members together; the latter having enlarged ends confined by the enlarged portion of the slot. 50
8. The combination of a slotted bar; said slot having an enlarged bottom portion, a plurality of thread-engaging members mounted in said slot, compressible metal spacing members disposed between said thread-engaging members, and means for clamping said thread-engaging and spacing members together; the latter having enlarged ends confined by the enlarged portion of the slot and the engaging portions of the clamping members being similarly shaped. 55

In witness whereof I have signed this specification.

W. B. KOCHENDERFER.
